FORK LIFT OR SIMILAR ARTICLE TRANSPORT VEHICLE

Bruce L. Renquist, Racine, Wis., assignor to J. I. Case
Company, Racine, Wis., a corporation of Wisconsin

Filed May 9, 1968, Ser. No. 11,871

Term of patent 14 years

Int. Cl. D12—13

U.S. Cl. D14—3

FIG. 1

FIG. 2

FIG. 4

FIG. 5

FIG. 3

FIGURE 1 is a perspective of the fork lift or similar article transport vehicle of my invention;

FIGURE 2 is a side elevational view of one side of the fork lift or similar article transport vehicle;

FIGURE 3 is a side elevational view of the opposite side of the fork lift or similar article transport vehicle;

FIGURE 4 is a view of one end of the fork lift or similar article transport vehicle; and

FIGURE 5 is an end view of the opposite end of the fork lift or similar article transport vehicle.

I claim:

The ornamental design for a fork lift or similar article transport vehicle, as shown.
